UNITED STATES PATENT OFFICE.

WALTER H. SMAW, OF NEW YORK, N. Y.

DESIGN FOR A MANDOLIN-BODY.

SPECIFICATION forming part of Design No. 31,918, dated December 5, 1899.

Application filed November 1, 1899. Serial No. 735,541. Term of patent 7 years.

To all whom it may concern:

Be it known that I, WALTER H. SMAW, a citizen of the United States, residing in the city of New York, borough of Brooklyn, in the county of Kings and State of New York, have invented and produced a new and original Design for a Mandolin-Body, of which the following is a full, clear, and exact description.

Reference is to be had to the accompanying drawings, forming a part of this specification, in which similar characters of reference indicate corresponding parts in both the views.

Figure 1 is a plan view of a mandolin-body, showing my design; and Fig. 2 is a side elevation of the same.

The design in its entirety consists of a body A, appearing flat in plan view, rounded off at its lower end A', its upper end terminating at the sides in arms B B', extending upwardly, and at the middle in a neck C, having a head D at the outer end, said arms being rounded

off at their upper ends and slightly curved outwardly, as at B², the lower portion A' of the body in side elevation appearing as decreasing in thickness from the bridge-line E downwardly, as plainly shown in Fig. 2.

The leading feature of the design consists of a flat body, with arms extending from the upper end of the body, at the sides thereof, and with a neck appearing between the arms.

Having described my invention, what I claim as new, and desire to secure by Letters Patent, is—

The design for a mandolin-body, as herein shown and described.

In testimony whereof I have signed my name to this specification in the presence of two subscribing witnesses.

WALTER H. SMAW.
